MOMENTARY SLOWDOWN DEVICE FOR
HIGH-SPEED BLANK HOLDER PRESSESRobert J. Lindsey, Mount Gilead, Ohio, assignor
to H-P-M Development Corporation, Wilming-
ton, Del., a corporation of Delaware

Application December 6, 1944, Serial No. 566,926

4 Claims. (Cl. 113—45)

1

This invention relates to control systems for blankholder presses. More particularly, this invention relates to a control system adapted to provide an improved operation of a blankholder press during the retraction stroke thereof.

In blankholder presses wherein the blankholder platen is carried by the main platen, the latter picks up the former during the retraction stroke of the press and returns it to its idling position. Usually, especially in the case of deep draws, the main platen has attained its full retraction speed before it reaches the position where it picks up the blankholder platen. The blankholder platen having considerable weight, the result of the main platen engaging it at full retraction speed is to create noise and vibration and, possibly, breakage of parts.

Accordingly, it is a primary object of this invention to provide a control system for a blankholder press which substantially prevents the main platen of a blankholder press from picking up the blankholder during the retraction stroke with a shock.

It is another object to accomplish the foregoing object by a fluid operable means.

It is another object to provide a control system for a blankholder press which has an automatic slow-down of the main platen during the advancing stroke and also during the retraction stroke thereof.

It is another object to provide cushioning means between the main platen of a blankholder press and the blankholder thereof operable to effect shockless engagement of the said blankholder by the main platen during the retraction stroke.

These and other objects and advantages will become more apparent upon references to the accompanying drawings, in which:

Figure 1 is a view of a blankholder press and control system therefor, shown diagrammatically;

Figure 2 is an enlarged sectional view showing a portion of the main platen of the press of Figure 1 and the cushioning means associated with the blankholder pick-up rod;

Figure 3 is a section taken on the line of 3—3 of Figure 2; and

Figure 4 is a diagram of the electrical portion of the control system.

General arrangement

A press adapted to be controlled by the control system of this invention comprises a main platen reciprocable toward and away from a stationary bed, the platen and bed mounting co-operating die portions so that a workpiece may

2

be shaped or drawn by the cooperation of the said die portions.

The platen has associated therewith a blankholder platen which is supported by the main platen by a plurality of rods and is permitted to move toward the main platen by a plurality of piston-cylinder means which serve to create the proper blankholding force, this latter function being accomplished by the provision of a relief valve or valves which maintains a predetermined and proper pressure within the said cylinders.

The aforementioned blankholder pick-up rods pass through lugs on the main platen which have cushion means therein so that the engagement of the main platen with the blankholder pick-up rods is substantially shockless.

According to this invention the main platen may be reciprocated by a double acting fluid operable ram to which is attached a suitable source of fluid pressure such as a reversible variable fluid delivery pump.

The aforementioned pump is controlled by linkage operable to place the said pump in full or partial delivery position in either direction or in neutral. The linkage is actuated by a piston-cylinder arrangement which is operated by pilot fluid conducted thereto from a plurality of pilot valves.

The said pilot valves are most conveniently operated by electrical means, the electrical means comprising limit switches responsive to predetermined movements of the main platen or to predetermined relative movements between the main platen and the blankholder platen.

According to this invention, one of the said pilot valves is actuated by a limit switch which is actuated just prior to the engagement of the main platen with the blankholder platen during the retraction stroke. The said valve is effective to actuate the piston-cylinder arrangement associated with the pump control linkage to shift the pump to reduced delivery position. Thus, the main platen is momentarily slowed down during the retraction stroke to affect the shockless cushioned engagement thereof with the blankholder platen.

Optionally, although not preferably, the slowdown of the main platen during its retraction stroke may be accomplished by timing the interval between the reversal thereof and the said slowing down.

Structural arrangement

Referring to the drawings more in detail, Figure 1 illustrates diagrammatically a blankholder press having a control system according to this in-

vention. The press comprises a bed 10 having a die cavity 12 therein, a main platen 14 which carries the punch 16 and a blankholder platen 18 which is supported by the main platen by the rods 20 and 22.

The main platen 14 is attached to a ram 24 which terminates at its upper end in the piston 26 which is reciprocable in the cylinder 28.

The cylinder 28 is connected, at its upper end, to the pump 30 by the conduit 32 and, at its lower end, to the pump 30 by the conduit 34. The conduit 34 has a branch conduit 36 connected therewith which extends into the reservoir 38 and connects with the outwardly opening check valve 40. Also connected with the lower end of the cylinder 28 is the pilot conduit 42 which connects with the surge valve 44 and opens the latter in response to a predetermined pressure in the lower portion of the cylinder 28.

Connected with the conduit 32 by a branch conduit 46 is a pressure switch 48 which, in response to a predetermined pressure on the upper surface of the piston 26, is adapted to open the circuit between the wires 50 and 52.

The platen 14 comprises a plurality of cylinders 54 within which are reciprocable the plungers 56, the latter being connected with the blankholder platen 18. The cylinders 54 are connected by a conduit 58 with an adjustable relief valve 60 and an inwardly opening check valve 62, the other sides of which are connected with the reservoir 38. During relative movement of the platens toward each other, the fluid in the cylinders 54 is expelled through the relief valve 60 and, during relative movement of the platens away from each other, the cylinders 54 are filled through the check valve 62.

The pump 30 comprises the servomotor 64, the actuation of which is effected by the control piston rod 66. A lever 68 is pivotally connected with the rod 66 and is rotatably supported on the servomotor 64 by the floating pivot 70. A drag link or pitman 72 is pivoted to the levers 68 at 74 and, to the lever 76 at 78. The lever 76 is secured to a stationary pivot at 80 and is also pivotally connected at 82 to the rod 84 which is integral with the plunger 86 reciprocably mounted in the bore 88 of the cylinder generally indicated at 90.

The opposite end of the lever 76 terminates in the angular portion 92 which is adapted to be engaged by the arm 94 of the platen 14 when the latter is in its fully retracted position.

The cylinder 90 comprises, in addition to the bore 88, the bores 96, 98, 100 and 102, these being separated by apertured partitions within the cylinder 90.

Reciprocably mounted in these separating partitions are the plungers 104, 106 and 108, each of which has a somewhat greater effective area than the plunger 86.

A conduit 110 connects into the cylinder 90 at the extreme right hand end thereof and also connects with the discharge port of the pump 112 whose suction port is connected with a reservoir 114. The discharge port 112 is also connected with the inlets of a plurality of valves 116, 118, 120 and 122 by the conduits 124, 126, 128 and 130, respectively. Each of the aforementioned valves comprises a valve member 132, 134, 136 and 138 which is urged downwardly by a suitable yielding means such as a spring.

Each valve piston is connected with the armature of a solenoid which, when energized serves to urge the valve member upwardly against the

thrust of the said springs. The solenoid-armature arrangements are indicated at 140, 142, 144 and 146.

The valve 116 comprises a discharge port 148 and a service line 150, the latter of which leads to the chamber 102 of the valve 90. The energization of the solenoid 140 is adapted to shift the valve member 132 into position to interconnect the conduits 124 and 150 thereby actuating the piston 104. The valve 118 is similarly arranged with a discharge port 152 and a service line 154 which leads into the chamber 100 of the valve 90. The valve 136 has an exhaust port 156 and a service line 158 which connects with the chamber 98 of the valve 90. As in the case of the valve 116, the energization of the solenoids 142 and 144 is adapted, respectively, to shift the valve members 134 and 136 into position to connect the conduits 126 and 154 and the conduits 128 and 158. The plungers 106 and 108 are thus, respectively, actuated.

The valve 122 comprises an exhaust port 160 and a service line 162 which leads into the chamber 96 of the valve 90. The spring in the valve 122 normally urges the valve member 138 into position to connect the conduits 130 and 162 so that the piston 86 is normally urged rightwardly. Energization of the solenoid 146 is adapted to move the valve member 138 into position to connect the conduit 162 with the exhaust port 160 thus exhausting the chamber 96.

The exhaust ports 148, 152, 156 and 160, if the fluid pumped by pump 112 is air, may exhaust into the atmosphere and, if the fluid is a hydraulic medium, may be connected with the reservoir 114.

Referring to Figures 2 and 3, there is shown the lugs or ears on the platen 14 through which the blankholder pick-up rods 20 and 22 pass. These lugs comprise a recess 180 within which are mounted a plurality of annular channel members 182 and a plurality of resilient annular members 184, the latter comprising a rubber-like material.

45 A ring 186 rests on the top of the uppermost of the members 104 and is adapted to abut the collar 188 of the rod 22. A plate 190 closes the top of the chamber 180 so that the ring 186 and resilient members are retained in place.

50 Mounted on the platen 14 adjacent the rod 22 is a limit switch 200 which comprises a roller 202 situated in the path of the collar 188. The switch 200 is so located that the roller 202 drops off the collar 188 slightly before the latter engages the ring 186. The switch 200 is adapted, when actuated by the collar 188, to close a circuit from the line 204 to the line 206 and also to the line 208.

This action occurs when the roller 202 is moved 60 toward its dotted line position in Figure 2 and the switch is idle when the roller is moved upwardly from its Figure 2 position, this occurring when the collar 188 is moved upwardly relative to the platen 14.

65 A second limit switch 210 is located so as to be actuated by the platen at a predetermined position during its downward travel. The actuation of the switch 210 is effective to close a circuit between the lines 212 and 214. The closing of this circuit is momentary and is reopened when the platen passes the said switch.

70 Referring to Figure 4, the electrical circuit by means of which the solenoids of the various pilot valves are energized is shown. In this figure the supply lines are indicated at 220 and 222. Con-

nected between the said supply lines is the contactor solenoid 224 which is adapted to be energized by the closing of the push button 226. The solenoid 224 is maintained energized by a holding circuit which includes the blades 224'. The solenoid 224 also closes the blades 224'' which are serially connected between the lines 220 and 222 with the solenoid 146.

Connected to the line 220 by the wire 212 is the limit switch 210 which is joined by the line 214 with the solenoid 140, the other end of which is connected to the power line 222.

The limit switch 200 is connected between the lines 220 and 222 in series with the solenoids 146 and 144 and is adapted, upon being actuated, to energize the said solenoids.

A contactor solenoid 226 is connected in series with the push button 228 with the power line and is adapted, when energized, to close the blades 226' and 226'', the former providing a holding circuit for the solenoid 226 and the latter being serially connected with the valve solenoid 142. A push button 229 is provided in the holding circuit of the solenoid 226 and is adapted to deenergize the said solenoid when actuated.

Operation

In operation, a working stroke of the press is instituted by closing the switch 226. This energizes the contactor solenoid 224 which holds on itself through the blades 224' and energizes the valve solenoid 146 through the blades 224''.

Energization of the valve solenoid 146 moves the piston member 138 upwardly thus interconnecting the conduit 162 and the exhaust port 160.

The chamber 96 being exhausted, the pressure standing in the chamber 88 is effective to move the piston 86 and piston rod 84 leftwardly thus actuating the linkage comprising the levers 76 and 68 to move piston rod 66 of the servomotor 64 into position to bring about the full delivery of the pump 30 into the upper end of the cylinder 28. The platens 14 and 18 are thus rapidly advanced toward work engaging position. Immediately prior to the engagement of the work by the blankholder platen 18 the switch 210 is actuated to energize the valve solenoid 140. Energization of the valve solenoid 140 moves the valve member 132 into position to interconnect the conduits 124 and 150 thereby supplying actuating fluid to the chamber 102. The piston 104 is thus actuated and, by means of its abutting relationship with the piston 106 and 108 moves the piston 86 rightwardly so that the aforementioned pump control linkage shifts the pump 30 into reduced delivery position. The downward movement of the platens 14 and 18 is thereby checked, so that the engagement thereof with the workpiece is accomplished at moderate speed and, therefore, without shock.

The switch 210 is deenergized as soon as the engagement with the work has been accomplished, or slightly prior thereto, and the circuit returns to its rapid advance position.

As the platen 14 continues downwardly with the blankholder platen 18 in engagement with the workpiece, the plungers 56 move into the cylinders 54 and expel fluid therefrom through the relief valve 69 thereby creating the proper blank holding pressure. At the same time the rods 20 and 22 move upwardly relative to the platen since they are rigidly attached to the blankholder.

After the main platen has completed its work

and built up a predetermined pressure in the upper end of the cylinder 28, the switch 48 is opened, thereby deenergizing the contactor solenoid 224 and the valve solenoid 146. The deenergization of the valve solenoid 146 again connects the conduits 130 and 162 and thus brings about the supply of pressure fluid to the chamber 96. The pressure in the chamber 96 urges the piston 86 rightwardly and, through the pump control linkage, moves the latter into position to deliver through the conduit 34 to the lower end of the piston 28. The ram 24 and main platen 14 thus commences their retraction stroke.

As the platen 14 moves upwardly, the collar 188 on the rod 22 moves downwardly relative to the said platen until it actuates the switch 200. Actuation of the switch 200 is effective simultaneously to energize the valve solenoids 146 and 144. Energization of these solenoids brings about the supply of pressure fluid to the chamber 98 while exhausting the chamber 96. The exhausting of the chamber 96 permits the piston 86 to move toward its forward delivery position while the supply of pressure fluid to the chamber 98 moves the piston 108 into position to abut the stop piston 86 at a point such that the pump 30 is delivering to the lower end of the cylinder 28 at a reduced rate.

Thus, the platen 14 moves into engagement with the collar 188 at reduced speed. Simultaneously with or slightly prior to the engagement of the collar 188 with the ring 186, the switch 200 opens so as to permit the pump control circuit to return the said pump into position to deliver at full rate into the conduit 34. During the interval that the pump is shifting from reduced delivery position into full delivery position, the platen 14, through the cushion member 184 and the collar 188, is gradually accelerating the blankholder platen 18. The blankholder platen 18 is thus picked up quietly and smoothly and without shock.

Should it be desired to halt the travel of the platen at any time during its downward movement the switch 228 may be closed thereby energizing the contactor solenoid 226 which holds on itself and energizes the valve solenoid 142 through the blades 226''.

The energization of the valve solenoid 142 brings about the supply of pressure fluid to the chamber 100 and actuates the piston 106 to move the piston 86 into its neutral position thereby centering the pump 30 and preventing the discharge therefrom in either direction. The downward stroke of the platen may be resumed by opening the switch 229 which deenergizes the solenoids 226 and 142.

At the end of the retraction stroke the platen arm 94 engages the portion 92 of the lever 76 and moves the pump control linkage into a neutral position.

It will be apparent that various modifications can be made in the structure shown without in any way departing from the spirit of this invention. For example, the pilot valves might be mechanically or hydraulically actuated rather than electrically. Also, as mentioned before, the interval between the commencing of a downward stroke and the initiating of the slow-down during the downward stroke could be a timed interval rather than an interval responsive to the travel of the platen. The initiation of the slowdown during the retraction stroke could also be accomplished by timing means rather than by positioning.

It will be understood that while certain embodiments of the present invention have been described herein, it is not intended thereby to have this invention limited to or circumscribed by the specific details of construction, arrangement of parts, procedures, or proportions herein described or illustrated in the annexed drawings in view of the fact that this invention is susceptible to modifications according to individual preference and conditions without departing from the spirit of this disclosure and the scope of the appended claims.

I claim:

1. The combination in a blankholder press of a main platen, a blankholder platen, a plurality of piston-cylinder means operatively associating said blankholder platen with said main platen, rods carried by said blankholder platen extending through said main platen and having collars thereon to limit the maximum spacing of said platens while permitting movement thereof toward each other, motor means for advancing said main platen into working position during which time said blankholder is moved toward said main platen and for retracting said main platen from said working position during which time said blankholder moves away from said main platen, means carried by said main platen to be engaged by one of said collars for retarding the speed of movement of said main platen immediately prior to the engagement thereof with said blankholder platen through said rods and collars, and means comprising annular resilient elements encircling said rods and interposed between said collars and said main platen whereby during the retracting movement of said main platen said blankholder platen is picked up smoothly and without shock.

2. In a press, a main platen, a blankholder platen, piston-cylinder means associating said platens, a rod attached to one of said platens and extending through the other for interconnecting said platens, a collar secured to said rod on the portion extending beyond said other platen for limiting the maximum spacing of said platens but permitting the movement thereof toward each other, a recess in said other platen around said rod opening toward said collar, annular resilient means in said recess to be engaged by said collar, fluid operable advancing and retracting means associated with said main platen for advancing and for retracting the same, a fluid source adapted selectively to deliver to one or the other of said means, control means associated with said fluid source operable to control the rate and direction of delivery thereof, means for actuating said control means to bring about the advancing movement of said main platen and for reversing the direction of movement of said platen, and other means operable in response to a predetermined retracting movement of said main platen away from said blankholder platen for actuating said control means to reduce the delivery thereof to said retracting means, the said other means including a limit switch carried by said other

platens and having its actuating element disposed to be actuated by said collar immediately prior to the engagement of said resilient means by said collar.

5 3. In a press which has a main platen and a blankholder platen suspended therefrom by members which limit the maximum spacing of said platens but permit the same to move toward each other and in which the main platen has 10 motor means for advancing it into working position and for rapidly retracting it from working position, the improvement comprising providing means for momentarily retarding the retracting speed of said main platen immediately prior to the engagement thereof with said blankholder platen through said members and thereafter restoring said main platen to its full retracting speed, said means comprising a limit switch and cam, one of which is carried by one of said platens and the other of which is carried by one of said members.

4. In a press which has a main platen and a blankholder platen suspended therefrom by members which limit the maximum spacing of said platens but permit the same to move toward each other and in which the main platen has 15 motor means for advancing it into working position and for rapidly retracting it from working position, the improvement comprising providing 20 resilient cushioning means between said members and one of said platens and also providing co-operating means on one of said platens and one of said members operable automatically and momentarily to retard the retracting speed of said 25 main platen in response to a predetermined spacing of said platens less than said maximum spacing thereof for effecting the engagement of said platens through said members and said cushioning means at reduced speed.
